RAILWAY TRAFFIC CONTROLLING APPARATUS

Chalmers W. Gilbert, Swissvale, Pa., assignor to
The Union Switch & Signal Company, Swiss-
vale, Pa., a corporation of Pennsylvania

Application January 3, 1936, Serial No. 57,357

9 Claims. (Cl. 246—46)

My invention relates to railway traffic controlling apparatus, and particularly to railway signaling systems utilizing signals each comprising a mechanism and a lamp.

- 5 One feature of my invention consists in improved and novel means for approach controlling the signal mechanisms and lamps, so that the mechanism and lamp for each signal are both normally deenergized and become energized when 10 a train is approaching the signal with which such mechanism and lamp are associated. In signal systems of the type herein involved, it is customary to rely upon primary batteries located along the trackway as the source of energy 15 for controlling and operating the signal mechanisms and for lighting the signal lamps. By my invention, a saving of the current output required from these batteries, which must be renewed from time to time, is accomplished. This 20 results in a material reduction in the cost of maintenance.

I will describe several forms of apparatus embodying my invention, and will then point out the novel features thereof in claims.

25 In the accompanying drawings, Fig. 1 is a diagrammatic view illustrating one form of signaling system embodying my invention. Figs. 2 and 3 are diagrammatic views illustrating modifications of portions of the system shown in Fig. 1, and each also embodying my invention.

Similar reference characters refer to similar parts in each of the several views.

In order to simplify the drawings, certain contacts are located at points not adjacent to the relays controlling the contacts. In each such instance, the reference character of the governing relay is placed just above the contact, and the contact is shown in a position corresponding to the normal condition of the relay. For example, the back contact 24 in the upper left-hand portion of Fig. 1 is governed by the approach lighting relay 2ER, and this contact is shown opened inasmuch as the relay is normally energized.

45 Referring first to Fig. 1, the rails 4 and 5 of a stretch of railway track over which traffic normally moves in the direction indicated by the arrow are divided by insulated joints 6 into track sections 1T, 2T and 3T. Each track section is provided with a track circuit including a source of current, such as a battery 7, and a track relay designated by the reference character R with a prefix the same as the reference character for the associated track section.

50 Traffic movements over this stretch of railway track are governed by signals spaced along the

stretch. Only signals 2 and 3 are shown in the drawings, but it is to be understood that there may also be similar signals in the rear of signal 2 and in advance of signal 3. These signals may be of any suitable type, and as here shown are searchlight signals, such for example, as described and claimed in United States Letters Patent No. 1,864,224, granted June 21, 1932, to W. B. Wells, for Light signal. For the purpose of this application, it is deemed sufficient to but 10 briefly describe these signals.

5 Signal 2, for example, includes a rotor 12 mounted to oscillate, and controlled by a permanent magnet (not shown) and by an operating winding 13. Energization of operating winding 13 by current of a given polarity causes rotor 12 to be rotated in a corresponding direction, moving the signal to the clear indication position; energization of operating winding 13 by current of the reverse polarity causes rotor 20 12 to be rotated in the opposite direction to move the signal to the caution indication position; while deenergization of operating winding 13 permits rotor 12 to be returned by gravity to a center 25 position, which is the stop indication position.

Associated with rotor 12 is a signal lamp 2E. As pointed out in detail in the aforementioned patent, when rotor 12 is rotated to the clear position, a green colored filter is moved in front of lamp 2E, causing a green signal light to be 30 displayed when lamp 2E is lighted. When rotor 12 is rotated to the caution indication position, a yellow colored filter is moved in front of lamp 2E, so that, with lamp 2E lighted, a yellow signal light is displayed. In like manner, the positioning of rotor 12 in the center position moves a red colored filter in front of lamp 2E and a red signal light is then displayed whenever lamp 2E is energized.

40 Rotor 12 actuates a set of circuit controlling contacts in such a manner that the contact 14—15 is closed only in the clear position and the contact 16—17 is closed only in the caution position. The reference characters G and Y are placed adjacent the contacts, indicating that the 45 contacts are closed in the clear and caution positions, respectively.

45 Each of the other signals, including signal 3, functions in a manner similar to that described for signal 2.

The source of energy for operating each signal mechanism and the relays associated with the control circuit for the same signal mechanism, and also for lighting the signal lamp for the next signal in advance, is a battery of proper 55

voltage located at the next signal in advance. In the drawings, these batteries are not shown, the two terminals for each battery being designated by the reference characters B and N with a prefix the same as the reference character of the signal at which the battery is located. For example, the reference character 3B designates the positive terminal of the battery located at signal 3 for operating the mechanism of signal 2 and 10 relays 2HP and 3ER, and for lighting the lamp for signal 3, and the reference character 3N designates the negative terminal of the same battery.

Associated with each signal is a pole changer relay designated by the reference character HP with a prefix which is the same as the reference character of the associated signal. Each relay HP also controls, in part, the lighting circuits for the associated signal. Each relay HP is controlled by the track relay for the section immediately in advance of the associated signal.

Each relay HP has a pickup circuit including a resistor designated by the reference character A with a prefix which is the same as the reference character for the associated signal, and has a stick circuit which by-passes the resistor A of its pickup circuit. Each resistor A reduces the current in the pickup circuit for the associated relay HP to such an extent that the relay HP is slow in picking up. Each relay HP, upon picking up, becomes energized by its stick circuit which, on account of not including the resistor A for its relay HP, over-energizes its relay HP, and therefore causes its relay HP to be slow in releasing.

It will be noted that each relay HP is controlled over a line circuit through a full-wave rectifier designated by the reference character Q with a prefix which is the same as the reference character of the associated signal. The relays HP, therefore, are always energized in the same direction, regardless of the polarity of the line control circuits. Due to this fact and to their slow release feature which is helped by snubbing circuits through the associated rectifiers, 45 these relays do not open their front contacts when the line circuits are pole-changed. This feature prevents tumble-down of the signals in the rear during changes of polarity of the line circuits.

Associated with each signal is an approach lighting relay designated by the reference character ER with a prefix which is the same as the reference character of the associated signal. Each ER relay is connected in series with the HP relay for the signal next in rear.

Each signal mechanism is controlled over the line circuit that controls the associated pole changing relay HP. Operating winding 13 of signal 2, for example, is controlled over a circuit which, when relay 3HP is energized, passes from terminal 3B, through the winding of approach lighting relay 3ER, front point of contact 21 of relay 3HP, wire 2H, front contact 22 of track relay 2TR, front contact 23 of relay 2HP, back contact 24 of approach lighting relay 2ER, operating winding 13 of signal 2, wire 2C, and front point of contact 25 of relay 3HP to terminal 3N. When relay 3HP is deenergized, the circuit for winding 13 of signal 2 passes from terminal 3B, through the winding of relay 3ER, back point of contact 21 of relay 3HP, wire 2C, operating winding 13, back contact 24 of relay 2ER, front contact 23 of relay 2HP, front contact 22 of relay 2TR, wire 2H, and back point of contact 25 of relay 3HP to terminal 3N. It will be seen, there-

fore, that when approach lighting relay 2ER becomes deenergized, so that its back contact 24 is closed, operating winding 13 of signal 2 will be energized by current of one polarity or another depending upon the condition of pole changing relay 3HP, provided, of course, that section 2T is unoccupied. It will be noted that pole changing relay 2HP is connected through the rectifier 2Q to the line circuit that controls signal 2.

It will also be noted that both signal 2 and relay 2HP are energized through resistor 2A when contact 23 of relay 2HP is open. Resistor 2A retards the pick up of relay 2HP and the operation of signal 2 so that both relay 2HP and operating winding 13 of signal 2 have a slow pick-up characteristic. This feature prevents a momentary clear indication in the event that relay 2TR becomes energized before relay 3HP releases when a high speed light engine passes from section 2T into section 3T.

Each signal and its associated HP relay is controlled through a resistor A in the same manner as just described for signal 2.

Each signal lamp E is controlled by circuits which are governed by contacts of the approach lighting relay and the pole changing relay for the signal with which such lamp is associated, as well as by contacts of the mechanism for that signal. For example, lamp 2E is provided with three circuits. One circuit passes from terminal 2B, through the front point of contact 16 of relay 2HP, back contact 11 of relay 2ER, clear contact 14-15 of signal 2, and lamp 2E to terminal 2N. The second circuit passes from terminal 2B, through the front point of contact 10 of relay 2HP, back contact 11 of relay 2ER, caution contact 16-17 of signal 2, and lamp 2E to terminal 2N. The third circuit passes from terminal 2B, through the back point of contact 18 of relay 2HP, and lamp 2E to terminal 2N. It will be seen, therefore, that when the mechanism of signal 2 is in its clear or caution condition, lamp 2E will be lighted when approach lighting relay 2ER becomes deenergized in response to the occupancy of section 1T by a train, and that when the mechanism of signal 2 is in its stop condition, lamp 2E will be lighted when relay 2HP becomes deenergized in response to the occupancy of section 2T by a train. Accordingly, when signal 2 is in its clear or caution position, lamp 2E will be lighted only when a train occupies section 1T, but when section 2T is occupied, lamp 2E will be lighted regardless of whether section 1T is or is not occupied.

With all parts of the apparatus in the normal condition, that is, with the operating windings 13 of the signals deenergized and with the lamps E extinguished, I shall assume that a train travelling in the direction indicated by the arrow enters section 1T, so that track relay 1TR will become deenergized. When relay 1TR is deenergized, approach lighting relay 2ER also will be deenergized, so that its back contacts 11 and 24 will become closed. When back contact 24 is closed, operating winding 13 of signal 2 will be energized by current of normal polarity over the previously traced line circuit, so that the mechanism of signal 2 will be operated to the proceed position. Signal mechanism contact 14-15 will therefore become closed to complete the first of the previously traced circuits for lamp 2E. Signal 2, therefore, will indicate proceed to the approaching train.

When the train enters section 2T, so that

track relay 2TR becomes deenergized, the opening of front contact 22 of relay 2TR will cut off energy from the mechanism of signal 2 and from relay 2HP. Signal 2, therefore, will assume its stop condition, and lamp 2E will be lighted over the previously traced lamp circuit which includes the back point of contact 10 of relay 2HP.

When the train vacates section 1T, so that its track relay again becomes energized, approach lighting relay 2ER will also become energized. The circuit for operating winding 13 of signal 2 is already open at contact 22 of relay 2TR, but will now be opened also at contact 24 of relay 2ER. Operating winding 13 of signal 2, therefore, will remain deenergized until the first train leaves section 2T and until another train enters section 1T.

When the first train enters section 3T, so that track relay 3TR becomes deenergized, the opening of its front contact 30 will cause relay 3HP to become deenergized. The deenergization of relay 3HP will reverse the polarity of the current supplied to the line circuit for signal 2, so that in the event of a following train occupying section 1T, signal 2 will display the caution indication when the first train vacates section 2T. The picking up of track relay 2TR again closes the circuit for relay 2HP, so that this relay becomes energized. When relay 2HP is energized, the third circuit traced for lamp 2E will be open due to the opening of the back point of contact 10 of relay 2HP. The second circuit traced for lamp 2E will then be closed on account of contact 10 of relay 2HP being closed at its front point.

When the first train leaves section 3T, so that relay 3TR again becomes energized, relay 3HP will be energized, so that the line circuit for signal 2 will be energized in the normal direction. A following train entering section 1T will now find signal 2 displaying the clear indication.

Referring next to Fig. 2, it will be noted that resistor 2A is connected between relay 2HP and rectifier 2Q instead of in the signal line circuit, and that signal 2 is governed by a front contact 31 of relay 2HP. It will be readily apparent that resistor 2A causes relay 2HP to have a slow pickup characteristic, and that signal 2 will necessarily be slow to respond to the energization of its line circuit, since operating winding 13 can not be energized until after relay 2HP has closed its front contacts. Otherwise, signal 2 and its associated apparatus functions in a manner similar to that described for the apparatus shown in Fig. 1.

It will be understood that each of the signals and associated pole changing relays of a signaling system embodying my invention may be controlled in a manner similar to that shown in Fig. 2.

Referring now to Fig. 3, the reference character 2F designates a resistor connected between the line control circuit for signal 2 and the associated rectifier 2Q. A branch path is provided around resistor 2F, which path is closed when the associated approach lighting relay 2ER is deenergized. For example, when relay 2ER becomes deenergized so that its back contacts 24 and 32 become closed, operating winding 13 becomes energized, and relay 2HP is energized through the branch path including the back point of contact 32. The value of resistor 2F is so chosen as to compensate for the drop in voltage due to the energization of operating winding

13. That is, relay 2HP is energized by current of a substantially constant value since, when operating winding 13 is deenergized, on account of relay 2ER being energized, so that the voltage across the line control circuit at rectifier 2Q is relatively high, resistor 2F is effective for reducing the current received by relay 2HP whereas, when signal 2 and relay 2HP are both energized so that the voltage across the line circuit is relatively low, resistor 2F is rendered ineffective.

It is to be understood that each of the signals and associated relays HP of a signaling system embodying my invention may be controlled in the modified manner shown in Fig. 3. This modification is particularly adapted for use under conditions where the voltage of the line circuit may vary over such a wide range as to interfere with the slow acting characteristics of the pole changing relays. Furthermore, the resistors F result in a saving of energy since they prevent excessive overenergization of the relays HP.

While I have herein shown and described my invention as applied to stretches of railway track over which trains normally move in only one direction, it is understood that my invention may also be applied to stretches of railway track over which trains move in both directions.

From the foregoing description of several forms of apparatus embodying my invention, it is apparent that I have provided a simple and reliable means for effecting a saving of energy in a railway signaling system. The signal mechanisms and associated lamps are normally deenergized, and are arranged to become energized only when a train is in the vicinity of such signals. Since, under normal conditions, the usual stretch of railway track is unoccupied for the greater portion of time, my invention will result in an appreciable saving in maintenance costs, particularly when the energy is supplied by primary batteries.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a stretch of railway track, a signal for said stretch, a relay governed in accordance with traffic conditions in advance of said signal, a second relay governed in accordance with traffic conditions in the rear of said signal, a lamp for said signal, circuits for lighting said lamp controlled by said two relays, and a mechanism for said signal controlled by said second relay.

2. In combination, a stretch of railway track, a signal having a normally inoperative mechanism associated therewith for said stretch, contacts governed by said mechanism, a relay governed in accordance with traffic conditions in advance of said signal, a second relay governed in accordance with traffic conditions in the rear of said signal, a lamp for said signal, circuits for said lamp governed by said two relays and by said contacts, and means controlled by traffic conditions adjacent said signal and conditioned by a train approaching said signal for operating said signal mechanism.

3. In combination, a stretch of railway track, a signal for said stretch, a line circuit for re-

- versibly governing said signal in accordance with traffic conditions in advance of the signal when said signal is connected with said line circuit, a neutral relay for reversibly governing the signal next in the rear, a rectifier for connecting said neutral relay with said line circuit, and an approach relay for connecting said first signal with said line circuit when a train is approaching said first signal.
- 10 4. In combination, a stretch of railway track, a signal for said stretch, a line circuit governed in accordance with traffic conditions in advance of the signal for controlling said signal when said signal is connected to said line circuit, a normally energized slow pickup relay connected to said line circuit, a normally energized approach relay arranged to be deenergized when a train is approaching said signal, and means including a front contact of said slow pickup relay and a back contact of said approach relay for connecting said signal to said line circuit.
- 5 5. In combination, a stretch of railway track, a signal for said stretch, a line circuit governed in accordance with traffic conditions in advance 25 of said signal for controlling said signal when said signal is connected to said line circuit, a relay for governing the signal next in the rear, means including a current limiting resistor for connecting said relay with said line circuit, a second relay for connecting said first signal with said line circuit when a train is approaching the first signal, and means including a contact of said second relay for rendering said resistor ineffective when said first signal is connected to 30 said line circuit thereby maintaining the current flow through said first mentioned relay at a substantially constant value even though the voltage across said line circuit decreases due to the current supplied to said first signal.
- 10 6. In combination, a stretch of railway track, a signal for said stretch, a line circuit governed in accordance with traffic conditions in advance of said signal for controlling said signal when said signal is connected to said line circuit, a relay connected with said line circuit for governing the supply of current to a second signal next

in the rear of said first signal, means for connecting said first signal with said line circuit when a train is approaching the first signal, and means including a resistor and controlled by traffic conditions in the rear of said first signal for maintaining the current supplied to said relay at a substantially constant value regardless of whether said first signal is connected to or disconnected from said line circuit.

7. In combination, a stretch of railway track, a signal comprising a mechanism and a lamp for governing traffic movements into said stretch, a relay, a resistor, a circuit including said resistor and controlled by traffic conditions adjacent said signal for energizing said mechanism in multiple with said relay with the resistor and source of current for said circuit so proportioned that the mechanism and relay are slow in picking up, a front contact of said relay connected in multiple with said resistor for increasing the current supplied to said relay to make said relay slow to release when the circuit is subsequently opened, and circuits controlled by said relay and by said mechanism for lighting said lamp.

8. In combination, a stretch of railway track, a signal for governing traffic movements into said stretch comprising a lamp and also comprising a mechanism operable to the proceed or caution condition by current of normal or reverse polarity respectively, a relay, a rectifier, a circuit controlled by traffic conditions adjacent said signal for energizing said relay through said rectifier by current of a given polarity and for energizing said mechanism in multiple with said rectifier and relay by current of normal and reverse polarities, and means controlled by said relay and by said mechanism for lighting said lamp.

9. In combination, a stretch of railway track, a signal for said stretch, a relay, a line circuit controlled by traffic conditions adjacent said signal for energizing said relay, and means including a front contact of said relay for energizing said signal from said line circuit in multiple with said relay to direct traffic movements in said stretch.

CHALMERS W. GILBERT.
